C. NIELSEN

GATE OPERATING DEVICE

Filed Oct. 10, 1921

Inventor
Chris Nielsen
by Doring & Hayes Atty's.

UNITED STATES PATENT OFFICE.

CHRIS NIELSEN, OF RUTHVEN, IOWA

GATE-OPERATING DEVICE.

Application filed October 10, 1921. Serial No. 506,908.

To all whom it may concern:

Be it known that I, CHRIS NIELSEN, a citizen of the United States, and resident of Ruthven, in the county of Palo Alto and State of Iowa, have invented a certain new and useful Gate-Operating Device, of which the following is a specification.

My invention relates to that class of gate operating devices in which the gate is supported for longitudinal movement to open and close, and the gate opening and closing device is operated by pulling on a lever at either side of the gate to open or close it.

My object is to provide a gate operating device of this class of simple, durable and inexpensive construction and which may be operated to open or close conveniently and easily and with a minimum of applied power.

More specifically it is my object to provide improved means for supporting the gate in its sliding, tilting movement and to combine with this gate supporting means an automatic latch device arranged to coact with a part of the gate guiding means to automatically lock the gate when it assumes its closed position; and

Furthermore in this connection, to provide means that coact with the gate opening lever for releasing the latch upon the initial movement of the gate operating levers.

My invention consists in the construction, arrangement and combination of the various parts of the device, whereby, the objects contemplated are attained as hereinafter more fully set forth, pointed out in my claims and illustrated in the accompanying drawings, in which:

Figure 1 shows a side elevation of a gate with my improved gate operating device applied thereto. In this figure the dotted lines show the gate in a partly open position and also in an open position.

Figure 2 shows a top or plan view of same.

Figure 3 shows an enlarged detail end view taken on line 3-3 of Figure 1.

Figure 4 shows a detail view illustrating the automatic latch device, and

Figure 5 shows a detail sectional view on the line 5-5 of Figure 3.

Referring to the accompanying drawings, I have used the reference numeral 10 to indicate the gate proper, which is of ordinary construction. In the present instance the gate is preferably made of a rectangular frame of pipes having woven wire fixed within the pipes.

Erected adjacent to one end of the gate are two uprights 11 spaced apart on opposite sides of the gate and connected at their upper ends by the brace 12.

In order to tiltingly and slidingly support the gate I have fixed to one end of the gate a cross bar 13 having slotted openings 14 in its ends, as shown in Figure 3. Fixed to the uprights 11 at one end and to stationary post 15 at the other end are two horizontally arranged guide rods 16 extending from the uprights 11 and in a direction opposite from the opening in the fence. By this means one end of the gate is slidingly supported above the ground.

At the lower ends of the uprights 11 is a cross bar 17 to which I have pivotally connected the levers 18, which levers extend upwardly and outwardly toward the center of the top of the gate, at which point they are united and connected to the top of the gate. Adjustably mounted upon these levers 18 are the collars 19 to which the rods 20 are connected. By this arrangement it will be seen that when either of the rods 20 is pulled upwardly the free end of the gate will be tilted upwardly to the position shown by dotted lines at the central portion of Figure 1, and the other end of the gate will slide longitudinally upon the guide rods 14 by reason of the cross piece 13 mounted thereon and fixed to that end of the gate, and a further movement of said levers 18 will cause the gate to move to its said open position, as shown by dotted lines at the left of Figure 1.

Mounted adjustably upon the upper end of each of the uprights 11 is a bracket 21 secured by set screws 22 so that it is both horizontally and vertically adjustable. Pivoted to the outer end of the bracket 21 is a

lever 23 pivoted by means of the bolt 24, as shown in Figure 5. This lever is preferably made of several pipes telescopically connected so that it is adjustable as to length. 5 The outer end of the lever 23 is connected to the rod 20 on the side opposite from the bracket 21 to which the lever is attached, as clearly shown in Figure 3. Upon the central portion of the lever 23 I provide a 10 weight 25 adjustably supported by the U-bolts 26. On the outer end of each of the levers 23 is a pulley 27, shown in Figure 1, and in the top of the bracket 21 is a guide loop 28, and upon the cross piece 12 is a 15 pulley 29. For each of the levers 23 there is a rope 30, its free end hangs straight down from the outer end of the lever 23, and the rope then passes over the pulley 27 and over the pulley 29. The ends of these two 20 ropes are connected at 31 and are attached to a latch device, the body portion of which is indicated by the numeral 32. This latch device is clearly shown in Figures 3 and 4 and has at its lower end a latch shoulder 25 33 and is provided with slots 34 through which the bolts 35 are passed, and these bolts are fixed to the adjacent uprights 11. I 30 preferably provide springs 36 on these bolts 35 to yieldingly hold the latch body substantially parallel with the uprights, which springs serve as cushions against the rebound of the gate when forcibly and rapidly moved to closed position, but the springs do not apply enough tension to prevent the 35 latch from moving down by gravity.

In the practical operation of my improved 40 gate operating device and assuming that it is in its closed position, it is obvious that the gate will be firmly held against all the strains to which gates are ordinarily subjected. Lateral movement of the gate by 45 pressure from either side is resisted by the cross piece 13 on the guide rods 16. Longitudinal movement of the gate is prevented by the latch engaging the cross piece 13 and vertical movement of the outer end of the gate is prevented by the latch device and the cross piece 13 on the inner end of the gate.

50 By reason of the vertically movable and horizontally adjustable bracket 21 the levers 23 may be placed in any conveniently accessible position. Further, the length of said levers may be adjusted by telescoping the sections of which the lever is formed.

Assuming that the gate is closed and it is 55 desired to open it, then the operator pulls downwardly upon the adjacent rope 30. The first effect of this pull is to raise the 60 latch device and when it has been raised to its limit and the rope can not be drawn further downwardly then the pull upon the rope is applied in a downward direction on the outer end of the lever 23. This will 65 raise the outer end of the gate and bodily

move the gate toward an open position, as indicated by the dotted lines in Figure 1 at the center thereof. Only one end of the gate is elevated because of the cross piece 13 and the guide rods 16. During this 70 opening movement of the gate the gate can not move laterally because of the cross piece 13 and the guide rods 16, and after the levers 19 have swung past a vertical position then the gate will move the rest of the way by 75 gravity to a fully open position.

The adjustable weight 25 is arranged so that it substantially counterbalances the weight of the gate so that the pull upon the rope by the operator need be only very 80 slight in order to accomplish the opening or closing movement. The same process is used when moving the gate from the open to closed position except that in this case it is not necessary to release the latch. 85

I claim as my invention:

1. The combination of a gate, an operating device comprising two uprights on opposite sides of the gate, a cross piece fixed to one end of the gate, and having openings 90 in its ends on opposite sides of the gate, two substantially horizontal guide rods fixed on opposite sides of the gate and extended through the openings of the said cross piece, a lever pivoted at its lower end to said uprights and connected at its upper end to substantially the central portion of the top of the gate, and means for operating said lever comprising a bracket adjustably mounted at the upper end of each of said uprights, a 95 lever fulcrumed to said bracket, a rod connected to the inner end of said lever and to the aforesaid lever that is connected to the gate, and a latch device normally engaging the said cross piece on the end of the gate, a rope connected to said latch device and slidingly supported on the lever that is attached to said bracket, and means for limiting the movement of the latch whereby the 100 pull upon said rope will first release the latch and then lower the outer end of the lever, substantially as and for the purposes 105 stated.

2. The combination of a gate, an operating device comprising two uprights on opposite sides of the gate, a cross piece fixed to one end of the gate, and having openings in its ends on opposite sides of the gate, two substantially horizontal guide rods fixed on opposite sides of the gate and extended through the openings of the said cross piece, a lever pivoted at its lower end to said uprights and connected at its upper end to substantially the central portion of the top of the gate, and means for operating said lever comprising a bracket adjustably mounted at the upper end of each of said uprights, a 115 lever fulcrumed to said bracket, said lever being longitudinally extensible and being 120 provided with an adjustable counterbalanc- 125 130

ing weight, a rod connected to the inner end of said lever and to the aforesaid lever that is connected to the gate, and a latch device normally engaging the said cross piece on the end of the gate, a rope connected to said latch device and slidably supported on the lever that is attached to

said bracket, and means for limiting the movement of the latch whereby the pull upon said rope will first release the latch 10 and then lower the outer end of the lever, substantially as and for the purposes stated.

Des Moines, Iowa, August 26, 1921.

CHRIS NIELSEN.
